[57] CLAIM

The ornamental design for a support for an inverted bottle,
as shown and described.

DESCRIPTION

FIG. 1 is a top plan view of a support for an inverted bottle
showing my new design;

FIG. 2 is a bottom plan view thereof;

FIG. 3 is a front elevational view thereof;

FIG. 4 is a back elevational view thereof; and,

FIG. 5 is a top perspective view thereof.

The broken line environmental illustration of a bottle in FIG.
5 is not part of the claimed design.
